THROTTLE ACTUATING MECHANISM

Vinton P. Birch, Birmingham, Mich., assignor to General Motors Corporation, Detroit, Mich., a corporation of Delaware

Application August 8, 1956, Serial No. 602,730

7 Claims. (Cl. 261—23)

The present invention relates to a throttle actuating mechanism for use with a carburetor of the type having a plurality of throttles which are adapted to be sequentially operated. A carburetor of this general type is shown in copending application S. N. 264,136, Olson, filed December 29, 1951, now Patent No. 2,771,282, dated November 20, 1956.

In carburetors of the type in which there are sequentially operating primary and secondary throttles, it is normal practice to provide means for locking the secondary throttle in a closed position until such time as the engine operating temperature reaches a given value to insure that the combustible mixture is not too lean during the time the engine is warming up.

It has been the practice heretofore to latch the secondary throttle in a closed position in accordance with the position of the choke valve. That is to say, when the choke is substantially closed, as is the case when the engine operating temperature is low, the secondary throttle will be maintained in a closed position. As the engine temperature increases and the choke valve is thereafter, either manually or automatically, moved to an open position, the choke opening force will unlatch the secondary throttle permitting the latter to be opened in accordance with operator demand. The mechanisms which have heretofore accomplished this result have had at least one undesirable operating characteristic which the present invention has eliminated. In order to permit full actuation of the primary throttle when the secondary throttle is latched closed, a lost motion mechanism is provided between the throttles and which mechanism usually includes a relative heavy overtravel spring which the operator must manually overcome to fully open the primary throttle. In the present invention a unique linkage mechanism is provided which eliminates the overtravel spring and its accompanying resistance to primary throttle actuation.

In the present invention, the position of the choke still determines whether or not the operative connection between the secondary and primary throttles is to be interrupted; however, the actual force utilized in effecting a change in the operative connection is supplied by the opening and closing movement of the primary throttles as dictated by the operator's actuation of the vehicle accelerator pedal.

Accordingly, the present invention provides a sequential throttle operating device which enables throttle actuation to be achieved with a considerably reduced effort on the part of the operator as well as reducing load on the accelerator pedal-to-throttle linkage mechanism. In both respects, these improved results also contribute to a simpler and more economically manufactured throttle actuating mechanism.

Additional objects and advantages of the present invention will be realized from a perusal of the detailed description which follows.

In the drawings:

2

Figure 1 shows a carburetor embodying the subject throttle actuating mechanism.

Figure 2 is a fragmentary view of Figure 1 in which part of the throttle actuating mechanism has been eliminated to better illustrate details.

Figure 3 shows an exploded perspective view of the throttle actuating mechanism.

While it is applicable to any carburetor utilizing sequentially operating throttles, the invention is shown in the environment of a four-barrel carburetor of the type shown and described in detail in copending application S. N. 264,136, Olson et al., filed December 29, 1951, now Patent No. 2,771,282, issued November 20, 1956. The subject carburetor, except as hereinafter specifically described functions in the same manner as in the aforementioned carburetor copending application and a detailed description thereof will not be made.

Referring to Figure 1, the carburetor is shown generally at 10 and includes a float bowl casing 12, a float bowl casing cover 14 and a throttle body 16. Disposed within the cover 14 is a choke valve 17 adapted to control the flow of air through the primary induction passages 18. Also, disposed in the primary induction passage posteriorly of the choke valve is a pair of primary throttles 20 which are pivotally mounted in the throttle body 16 upon a shaft 22. A secondary or auxiliary induction passage is shown generally at 24 and includes a pair of throttle valves 26 fixed to shaft 28 for rotation therewith.

Choke valve 17 is of the automatic type and is offset with respect to its shaft 30 so as to be responsive to the flow of air theretofore. Further, choke valve 17 is automatically controlled in accordance with engine temperature and manifold vacuum through a device of the type shown and described in the aforementioned copending application. The operation of the automatic choke is such that when the engine operating temperature is low the thermostat maintains the choke in a closed position gradually permitting the choke to open under the influence of manifold vacuum and air flow as the engine temperature increases.

A throttle operating lever 32 is fixed to the primary throttle shaft 22 and includes an arm 34 adapted to be suitably articulated at one end to a throttle rod 36 which is controlled by the accelerator pedal in such a way that as the accelerator pedal is depressed the throttle rod 36 rotates the lever 32 in a clockwise direction to open the primary throttles 20. Arm 34 of lever 32 is offset and has a tab 38 adapted to threadably receive an idle adjusting screw 40 which is adapted to coact with a fast idle cam 42 pivotally mounted upon the throttle body 16 through a stud 44. The fast idle cam 42 is connected intermediate its ends to one end of a link 46, the other end of which link is pivotally connected to the choke shaft 30 through a suitable lever 48.

As the choke valve opens, the fast idle cam is rotated in a counterclockwise direction permitting the idle adjusting screw 40 to engage with the progressively lower steps on the cam periphery as the engine warms up and higher idling speeds become unnecessary. The fast idle cam also includes a deloading tang 50 which is adapted to be engaged by an offset arm 52 projecting from lever 32. The arm is adapted, when the throttle is moved to a wide open position, to engage tang 50 and thereby positively open the choke valve 17 to unload the primary induction passage to atmosphere.

Mounted on the primary throttle shaft 22 is a lever 54 which is adapted to be moved axially as well as rotarily relative thereto. Lever 54 includes arms 56 and 58. Arm 56 is pivotally connected at one end to a link 60, the other end of which is pivotally connected to a sec-

ondary throttle actuating lever 62. Lever 62 is fixed to the secondary throttle shaft 28.

Primary throttle actuating lever 32 has a tang or projection 66 extending therefrom which is adapted upon rotation of the lever to engage arm 56 to rotate lever 54 and thence secondary throttle shaft lever 62. Tang 66 and arm 56 are so arcuately oriented as to permit the primary throttles 20 to open a given amount, e. g. 40°, before engagement takes place and secondary throttle actuation is begun. In this way, normal engine power is regulated by the primary throttles with the secondary throttles being actuated only under conditions of high power demand.

In order to insure, however, even when the operator moves the primary throttle to the point where secondary throttle operation would normally begin, that such secondary throttle actuation does not take place due to low engine temperature, it is necessary to provide a means for rendering the secondary throttle inoperative. To this end a member 70 is provided which is pivotally supported at one end to choke link 46. The other end of member 70 is bifurcated so as to provide an open-ended slot 71 which is adapted to surround and be supported upon the primary throttle shaft 22. Member 70 is supported by shaft 22 and link 46 in such a way as to be axially movable with respect thereto. Intermediate the ends of member 70 there is an upstruck cam surface 72 which projects in the direction of the primary throttle lever 32. In the position as shown in Figure 3, there is an upstruck portion or follower 74 formed on lever 32 and which follower is adapted to coact with cam surface 72 in a manner to be hereinafter described.

A spring 78 is mounted on the primary throttle shaft 22 and seats against a shoulder 80 to urge lever 54 and member 70 axially into juxtaposition relative to the primary throttle lever 32.

With the choke valve 17 closed the choke link 46 will maintain the right end of member 70 in a raised position in which the cam follower member or tang 74 of lever 32 is in alignment with the cam surface 72 and disposed immediately thereabove. Thereafter, as the primary throttle lever is rotated in a clockwise direction to open the primary throttle, the follower member 74 will engage the cam surface 72, as seen in Figure 1, forcing member 70 and abutting lever 54 axially away from the primary throttle lever against the force of spring 78. In so doing, arm 56 of lever 54 is moved axially out of the range of contact by tang 66 on lever 32. Thus, the rotation of the primary throttle causes a portion of the linkage mechanism connecting the primary and secondary throttles to be shifted to a neutral position such that further opening of the primary throttles will have no effect on the opening of the secondary throttles.

As engine temperature increases to a point where the choke valve can be opened to reduce the richness of the operating mixture, the choke link 46 will move downwardly, under the force of gravity, moving the right end of member 70 downwardly and thereby causing the cam surface 72 to be moved to a non-cooperating position with respect to the cam follower tang 74 on the primary throttle lever 32. Thus, with the engine sufficiently warm, rotation of the primary throttle to the aforementioned 40° position will cause tang 66 to engage arm 56 of lever 54 rotating the latter in a clockwise direction and thereby imparting a counterclockwise movement to secondary throttle lever 62 which opens the secondary throttles 26.

The secondary throttle shaft has coiled thereabout a torsion spring 84 which tends to urge the secondary throttles toward a closed position.

With the mechanism provided by applicant the operator in moving the throttle from a closed to an open position experiences a substantially continuous and essentially light reaction to throttle pedal movement in contradistinction to the previous devices in which a heavy resistance had to be overcome when the secondary throttles were ren-

dered inoperative because of insufficient engine operating temperatures.

I claim:

1. A carburetor comprising first and second induction passages, throttle valves for respectively controlling the flow through said induction passages, a mechanism for controlling the actuation of the first throttle, a linkage device operatively connecting said first and second throttles for sequential operation, temperature responsive means connected to said device, said temperature responsive means adapted to coact with said first throttle controlling mechanism to disconnect the operative connection between said throttles when said engine temperature is low, and means urging said second throttle toward a closed position relative to said second induction passage.

2. A carburetor comprising first and second induction passages, a shaft extending transversely through each of said induction passages, throttle valves mounted on each of said shafts for respectively controlling the flow through the associated passage, a linkage device for operatively connecting said first and second throttles for sequential operation, temperature responsive means connected to said device and adapted when the engine temperature is low to move a portion of said device to a position in which the opening movement of said first throttle shifts a portion of said linkage device axially relative to at least one of said shafts to disconnect the operative connection between said throttles.

3. A carburetor including first and second induction passages, a throttle valve mounted on a shaft in each passage to control flow therethrough, first and second levers respectively fixed to said throttle shafts for rotation therewith, means for controlling the actuation of one of said levers, a third lever mounted for axial movement on the first induction passage throttle shaft and engageable by the first lever, a link between said second and third levers, a thermostatically controlled element disposed intermediate said first and third levers, said element being movable to a position when engine temperature is low in which the element is engageable by the first lever during open movement to shift the third lever axially out of engagement with the first lever, and means biasing said first and third levers into operative engagement.

4. A carburetor having primary and secondary induction passages, a throttle valve pivotally mounted on a shaft in each passage to control the flow of air therethrough, a temperature responsive choke mounted in the primary induction passage anteriorly of the throttle valve, linkage means connecting said throttle valves for sequential operation, said means including first and second levers respectively fixed to the primary and secondary throttle shafts, a pair of elements supported upon the primary shaft for axial and rotary movement relative thereto, means biasing said elements axially into operative engagement with the first lever, one of said elements being articulated to said second lever whereby rotary movement of the primary throttle shaft may be transmitted to the secondary throttle shaft, the other of said elements being articulated to said choke, the choke controlled element being movable to a position when engine temperature is low in which the rotary opening movement of the first lever will shift the elements axially to interrupt the operative connection between said throttle valves.

5. A carburetor having primary and secondary induction passages, a throttle valve pivotally mounted on a shaft in each passage to control the flow of air therethrough, a choke valve mounted in the primary induction passage anteriorly of the throttle valve, linkage means connecting said throttle valves for sequential operation, said means including first and second levers respectively fixed to the primary and secondary throttle shafts, a pair of elements supported upon the primary shaft for axial and rotary movement relative thereto, means biasing said

elements axially into operative engagement with the first lever, one of said elements being articulated to said second lever and the other element to said choke whereby rotary movement of the primary throttle shaft may be transmitted to the secondary throttle shaft, said choke controlled element having a cam surface thereon, said first lever including a portion adapted to engage said cam surface when said choke valve is in a substantially closed position enabling rotation of said first lever to shift said elements axially to interrupt the operative connection between said throttle valves.

6. A carburetor comprising primary and secondary induction passages; throttle valves mounted on shafts in said passages to control flow therethrough; a choke valve disposed in said primary passage anteriorly of the throttle; a linkage mechanism operatively connecting said throttles for sequential operation, and a device operated by said choke valve which causes the opening movement of the primary throttle to disconnect the operative connection between said throttles when the choke is in a

substantially closed position permitting the primary throttle to open without opening the secondary throttle.

7. A carburetor including first and second induction passages, a throttle valve mounted on a shaft in each passage to control flow therethrough, first and second levers respectively fixed to said throttle shafts for rotation therewith, means for controlling the actuation of one of said levers, a third lever mounted for axial movement on the first induction passage throttle shaft and engageable by the first lever, a rigid link articulated between said second and third levers, an element movable to a position in which it is engaged by the opening movement of said first lever to shift the third lever axially out of engagement with the first lever, and means normally biasing said first and third levers into operative engagement.
